EDWIN S. PRIDHAM, OF OAKLAND, AND DONALD K. LIPPINCOTT, OF ALAMEDA, CALIFORNIA, ASSIGNORS TO THE MAGNAVOX COMPANY, OF OAKLAND, CALIFORNIA, A CORPORATION OF ARIZONA.

GANG CONDENSER AND METHOD OF ADJUSTING SAME.

Application filed March 17, 1926. Serial No. 95,169.

This invention relates to variable gang condensers for use in radio and other high frequency work.

In order to simplify the tuning of a receiving set it is desirable to mount a number of condensers on a single shaft so that they may be moved simultaneously with a single control. It is essential to the successful operation of such gang condensers that the 10 capacities of the units be equal at the various positions of the rotor. The object of the present invention is to facilitate adjustment of the units during assembly to insure equal capacities. For this purpose we so mount 15 the stator units in a frame that individually they may be conveniently shifted laterally in either direction and at either end. Each unit of the gang condenser is then connected in turn in an oscillating circuit wherein the 20 tuning coil associated with the condenser forms the inductance and the condenser unit forms the capacity. This oscillating circuit may then be used as a standard and each unit brought into resonance therewith in all 25 positions of the rotor, by laterally shifting the stators. Once the proper adjustment of the stators is obtained they can be permanently fixed.

One form which our invention may assume 30 is exemplified in the following description and illustrated in the accompanying drawings, in which

Fig. 1 shows a perspective view of the condenser;

Fig. 2 shows a plan view of the same;

Fig. 3 shows a sectional view taken on the line 3—3 of Fig. 2;

Fig. 4 shows a similar view of the condenser with the rotor in open position;

Fig. 5 shows an end view of the stator, illustrating the shiftable connection between the end of the stator and the frame;

Fig. 6 shows a perspective view of the adjusting wrench used for shifting the stator.

Referring in detail to the accompanying drawing, the condenser therein illustrated comprises a rectangular frame 10 within which a plurality of stators are mounted, there being three stators in the present device. Each stator comprises spaced plates 11 soldered at their ends to cross-plates 12. Each cross-plate has a shifting bar 13 arranged on its inner face and carrying a pair

of bolts 14 which extend through slots 15 in the cross-plates and thence through openings in the frame 10. There is a keyway 16 in each cross-plate, arranged in juxtaposition with an opening or socket 17 in the frame. A wrench 18, as shown in Fig. 6, is inserted in the opening or socket 17 and has an eccentric pin 19 to engage in the keyway 16 for the purpose of shifting the stators laterally in either direction before the bolts 14 are tightened.

Between the stators we arrange shield plates 20, which are provided with ground connections 21. These plates are also shiftable laterally and serve to vary the minimum capacity of the condenser units.

The rotors of the condenser are mounted upon a shaft 22 journaled in the frame. Each rotor consists of spaced plates 23 soldered to a sleeve or barrel 24. The sleeve is fitted over the shaft 22 and locked in place thereon by screws 25 passing through hubs 26 on either end of the sleeve. The sleeve serves to space the plates apart, and they are additionally spaced and reinforced by lugs 27 at one end, which lugs are overlapped and soldered. To improve the connection between the rotor sections and conceal the soldered joints we prefer to arrange a semi-circular plate 28 on the shaft overlying the sleeves 24.

In assembling the condenser the plates of the stator sections are arranged in a jig and soldered to the cross-plates 12. The stator sections are next loosely mounted in the frame. The rotor sections are likewise arranged in a jig and soldered to the brass 90 sleeves 24, and the end lugs likewise soldered together. The rotors are then mounted on the shaft 22 and fastened thereto in parallel relation by means of a jig or gauge.

At this time we connect in turn each unit 95 of the gang condenser in an oscillating circuit, the tuning coil of the particular set forming the inductance and the unit condenser of the gang forming the capacity. We now choose a standard frequency for 100 comparison purposes. Adjustment of the stator of the test condenser is then made until the frequency of the test circuit is equal to the frequency of the standard circuit. In like manner the capacities of the other condensers of the gang are so adjusted

that the respective frequencies of the circuits of which they form a part are equal to the chosen standard.

A new standard frequency is then chosen, 5 such that if the first standard frequency chosen should utilize the maximum capacity of the test condenser, then the new standard is chosen so as to use about one-half the capacity of the test condenser. Adjustments of 10 the stators are again made so that the frequency in each circuit is made equal to the new standard frequency. This result must of course be obtained without upsetting the previously equalized capacities.

15 As many standard frequencies may be used as desired, and for each standard the several units are made equal to each other by being made equal to the standard. Thus, if at a number of points on the dial the 20 capacities are equal, it is a safe assumption that from maximum to minimum the capacities of the various units are equalized.

The work of equalizing the test circuits with the standard is made easy by the fact 25 that if the two circuits are not in perfect resonance a heterodyne note is heard in a detector circuit; adjustment is then made until this note disappears; and then it is known that the two circuits are in perfect 30 resonance.

There are other methods of determining when the two circuits are in perfect resonance, as, for instance, measuring the peak of current with a meter; but the heterodyne 35 method lends itself so well to large production that it is the preferred method.

Should there be any heterodyne beat in the circuit when the rotor sections are at zero, then the minimum capacity of the condenser can be adjusted by varying the position of the adjacent shield plates 20. When 40 all of the condensers are at equal capacities the bolts 14 are tightened and permanently secured.

In and by the present invention we are

enabled to readily and easily equalize the capacities of a gang condenser during assembly and set them permanently in position within the frame, thus obviating the necessity for any individual adjustment or tuning 50 thereafter. By thus accurately balancing and equalizing the capacities of the several condensers, a unit control may be employed with entire satisfaction.

Various changes in the construction and 55 arrangement of the several parts herein shown may be employed without departing from the spirit of our invention as disclosed in the appended claims.

Having thus described our invention, what 60 we claim as new and desire to secure by Letters Patent is:

1. In a condenser, a plurality of stators, each formed of spaced plates, a cross-plate at each end of each stator section, a shiftable 65 bar carried by each cross-plate, bolts connected to the shiftable bar and extending through slots in the cross-plate, a frame for the stator sections having openings through which said bolts extend, and means insertable through the frame to engage the cross-plates for shifting the same laterally to permit 70 adjustment during assembly.

2. In a condenser, a plurality of stators, each formed of spaced plates, a cross plate 75 at each end of each stator section and having a plurality of elongated slots therein, a shiftable bar carried by each cross plate, bolts connected to the shiftable bar and extending through a pair of the slots in the cross plate, 80 a frame for the stator sections having openings through which the bolts extend, and means insertable through the frame and having engagement with the other of said elongated slots in the cross plate for shifting 85 the same laterally to permit adjustment of the stators during assembly.
